ATTORNEYS

UNITED STATES PATENT OFFICE.

HERMAN O. REIDENBACH, OF DETROIT, MICHIGAN, ASSIGNOR TO L. A. YOUNG INDUSTRIES, INC., OF DETROIT, MICHIGAN.

SPRING STRUCTURE.

Application filed May 5, 1922. Serial No. 558,699.

To all whom it may concern:

Be it known that I, HERMAN O. REIDENBACH, a citizen of the United States, residing at Detroit, county of Wayne, State of Michigan, have invented certain new and useful Improvements in Spring Structures, of which the following is a specification.

This invention relates to improvements in spring structures.

10 The main object of this invention is to provide in a spring structure an improved means for supporting the springs in upright position and providing a resilient top or surface on which the upholstering or mattress may rest.

Further objects, and objects pertaining to details and economies of construction will definitely appear from the detailed description to follow.

20 A structure which is a preferred embodiment of the invention is fully illustrated in the accompanying drawing forming a part of this specification, in which:

The drawing is a plan view of a spring structure embodying the features of my invention, the same being shown in miniature form for convenience in illustrating, and the base or support being omitted.

Referring to the drawing, I provide a 30 plurality of springs 1 which are arranged in rows, the outer springs being secured to the border frame 2 by means of the clips 3. The structure illustrated has only nine springs but it will be understood that it is 35 shown in this form for convenience in illustration, my improvements being especially designed for large cushions, bed springs or the like.

Between each row of springs I arrange a 40 flat metal strip 4 of steel or pliant material adapted to yield freely under stresses. These cross strips are secured at their ends to the border frame and are provided with holes 5 located centrally relative to the 45 springs in the rows. The coiled spring ties 6 are arranged radially of the springs with their outer ends in these holes 5. Thus secured the springs are arranged in diverging pairs so that they effectively support the 50 springs against movement in all directions and, at the same time, yield freely to allow the springs to yield under pressure. The

cross strips 4 are thus connected to the springs so that the whole top of the spring structure may yield together or it may yield 55 locally.

Further, by this arrangement, I secure a very desirable surface for supporting a mattress or the upholstering.

I have not attempted to illustrate certain 60 embodiments and adaptations which I contemplate, and, as stated, I have illustrated a miniature structure, or one having only nine springs. It will be understood, however, that my improvements are desirable for 65 use in various types of cushion springs, bed springs and the like.

Having thus described my invention what I claim as new and desire to secure by Letters Patent is:

70

1. In a spring structure, the combination with a border frame, of a plurality of body springs disposed in rows, the outer springs being secured to said border frame, cross straps of pliant metal disposed between the 75 rows of springs, said straps having pairs of holes located centrally relative to the springs in the rows, and coiled spring ties disposed in diverging pairs with their adjacent ends engaged in said holes and their 80 other ends engaged with the coils of adjacent pairs of springs.

2. In a spring structure, the combination with a border frame, of a plurality of upright body springs disposed in rows, the 85 outer springs being secured to said border frame, cross straps of pliant metal disposed centrally between the rows of springs, and coiled spring ties disposed radially of the springs and connected thereto at one end, 90 their other ends being connected to the said pliant straps.

3. In a spring structure, the combination with a border frame, a plurality of body springs disposed in rows, pliant cross strips 95 disposed between rows of springs and secured to said border frame, and coiled spring ties connected to said springs and to said cross strips, said ties being disposed to support said springs in an upright position centrally between said cross strips.

In witness whereof, I have hereunto set my hand and seal.

HERMAN O. REIDENBACH. [L. S.]
